UNITED STATES PATENT OFFICE

RAY A. BROWN, OF ROCKFORD, ILLINOIS

STEREOTYPE-CASTING MACHINE

Application filed November 16, 1928. Serial No. 319,775.

This invention relates to stereotype casting machines of the kind especially adapted for use by small newspaper publishers and in jobbing and other printing shops for casting stereotype plates from matrices furnished by newspaper, advertising and other service agencies. The principles of my invention are, however, not limited to stereotype casting machines of this particular size or for this particular use, but are generally applicable in the casting of stereotype plates.

One of the primary objects of my invention is to provide a generally improved and simplified stereotype casting machine of the character described which will be easy to operate and thoroughly practical for the purposes intended.

My invention contemplates the provision of a relatively low standard or frame upon which is mounted a casting box, a melting pot, a carriage and a suitable means for heating. The casting box, consisting preferably of an upper and a lower platen pivotally connected at the upper ends, is mounted on the frame so as to swing from a horizontal matrice or work-receiving position to a vertical pouring position. The melting pot, in the present embodiment of my invention, is supported by a carriage which in turn rests upon a series of small wheels or rollers. The top of the supporting frame is provided with a track which permits the melting pot and carriage to be easily moved back and forth upon the rollers. By reason of the melting pot being moved horizontally on a smooth track and being bottom pouring there is little or no danger of injury from the metal splashing or spilling over. Consequently, the machine may be operated quickly and efficiently by one not especially skilled in the work.

In the drawings—

Figure 1 is a side elevation of a machine embodying my invention showing the casting box in the work-receiving position and the melting pot and carriage in the heating position;

Fig. 2 is a side elevation of the machine showing the casting box in the pouring posi-

tion and the melting pot and carriage in the heating position;

Fig. 3 is a side elevation of the machine showing the casting box and melting pot and carriage in the pouring position; and

Fig. 4 is a front view of the machine showing the casting box in the work-receiving position with the platens clamped together. The dotted lines show the casting box in the pouring position.

The casting box may be of any suitable construction. In the present case it is composed of a lower and an upper platen designated by 5 and 6, respectively. Cast integrally with the lower platen are the lugs 7 to which the upper platen is hinged by means of the bolts 8 so that it may be swung into open and closed positions to permit the placing of the matrices and gauges and the clamping of the same between the platens. The casting box 70 may be clamped in a closed position by any suitable means, in this instance by a suitable number of screw clamps 9 mounted on the lower platen and adapted to be swung into and out of the operative position. The casting box 75 may be supported by any suitable means so as to be capable of swinging back and forth between a horizontally disposed work-receiving position and a vertically disposed pouring or metal-receiving position on 80 the trunnions 10 journaled on the side members of the frame 11.

A simple means for holding the casting box in either the work-receiving or the metal-pouring position is provided. This consists of a 85 pendent lever 12 mounted on a bracket 13 with its edge bearing against the end of the trunnion 10, the end of the trunnion being slotted as shown at 14 to receive the lever at the desired work-receiving and metal-receiving positions of the casting box. It will be seen that the casting box may not be swung from one position to the other without first raising the lever 12 to clear the slots 14 in the trunnion 10.

The melting pot 15 serves as a pot for melting and a reservoir for holding the metal for casting the plates. The pot has an open top and a bottom pouring spout and is supported on a traveling carriage 17 by the lugs or seats 100

18 whereby a space is maintained between the sides of the melting pot and the walls of the carriage for the escape of waste gases from the heating means. The flow of metal 5 from the pot is regulated by a lever 19 pivotally mounted on the pot at 20, to which lever is attached a counter-balancing weight 21 and a rod 22 which actuates a suitable plunger located in the spout 16 but not shown since 10 it is well known in the art.

The carriage may take any suitable form whereby the pot may be moved horizontally from a point at one end of the frame designated as the heating position to a point at 15 the other end of the frame over the casting box designated as the pouring position. In the drawings I have shown a preferred form in which the carriage 17 is provided at the base with a number of rollers 23 designed to roll 20 or travel along a track on the top of the frame. Carriage extensions 25 projecting to a point below the horizontal members of the frame are equipped with rollers 26 which bear upwardly against said members to keep the carriage 25 from tipping while being moved from position to position or from being accidentally overturned. The extensions also serve as stops, bearing against the trunnions 10 when the melting pot has reached the pouring position. Any suitable means may be used for 30 heating the melting pot such as a gas, oil or electric heater. I show here a gas burner 27 supplied by gas from a pipe 28 and supported by a bracket 29 attached to the frame. A hook 24 on the carriage is provided to hold the upper platen in its proper place while the casting box is in the work-receiving position. The ends of the carriage are open to provide for the admission of air to the heater 35 under the pot when necessary, and to permit a heating means to be used which is permanently attached to the frame, the carriage passing to a point over the heater when brought into the heating position.

40 45 In the operating of my machine the normal idle position is shown in Fig. 1. We will assume that the burner is lighted and the metal is being melted. The upper platen 6, due to its close proximity to the burner and melting pot will be heated and partially prepared for the casting operation. The lower platen 5 should be heated prior to the casting operation by closing the casting box and casting a blank slug. The operator 50 should then set up the matrices and gauges in the usual manner and clamp the upper platen down in position by means of the clamps 9 thus putting the casting box in condition for pouring. Upon then releasing 60 the lever 12 the casting box may be swung into the vertical casting position. When the casting box has been rotated to the proper position for casting the lever 12 will drop into the slot in the trunnion and hold 65 the box in a fixed position ready for pour-

ing. The melting pot and carriage may then be moved from the heating position to the pouring position by sliding them along the track until the extensions 25 are brought against the trunnions 10, when the melting pot is also in position for pouring. The operator may then pour by depressing the lever 19 until sufficient metal has escaped to fill the mold. Reversing the operations brings the casting box and melting pot back 70 to their original positions.

75 It will be evident that the operations required are very easily performed. The roller mounted carriage permits the melting pot to be easily and safely moved from the heating position to the casting position. The extensions 25 positively prevent the melting pot from being drawn beyond the pouring position by the operator. Because of the counterbalanced mounting of the 80 casting box it is easily swung from one position to the other, and the lever 12 positively locks it in the proper position.

85 It is believed that the foregoing conveys a clear understanding of the objects of the invention, and while I have illustrated but a single working embodiment, it should be understood that changes might be made in the construction and arrangement without departing from the spirit and scope of the 90 invention.

95 I claim:

1. A stereotype casting machine comprising a frame supporting a casting box including an upper and lower platen pivotally mounted on said frame to rotate from a work-receiving position to a metal-pouring position, a melting pot, and a wheel-supported carriage carrying said melting pot adapted to travel on the frame from a heating position at one end of said carriage to a pouring position centrally over said casting box when the latter occupies the metal pouring position, one end of said casting box in the work receiving position lying next to said carriage in the heating position, and means acting between said carriage and said upper platen for securing the latter in an open position.

tracks whereby it may travel horizontally from a heating position at one end of said frame to a pouring position, over said casting box, carriage extensions projecting downward from said carriage, and rollers 5 attached to said carriage extensions, adapted to cooperate with said lower tracks, to prevent said carriage from tipping when being moved from position to position, said carriage extensions being adapted to stop 10 against said trunnions to determine the pouring position of said carriage.

3. A stereotype casting machine comprising a frame, a casting box including an upper and a lower platen, the former being 15 pivotally mounted upon the latter, means for clamping the platens together, trunnions on the lower platen journaled on the frame, one of said trunnions extending beyond said frame and provided with cross slots, means 20 engageable in said slots for holding the casting box fixedly in either a work-receiving position or a metal-pouring position, a bottom pouring melting pot having a plunger for controlling the flow of metal and a lever 25 for operating said plunger, and a carriage supporting said melting pot resting upon rollers and adapted to move upon a track from a heating position at one end of the frame to a pouring position at the other.

30 In witness of the foregoing I affix my signature.

RAY A. BROWN.
